UNITED STATES PATENT OFFICE.

STEPHEN S. WARD, OF GREENFIELD, MASSACHUSETTS.

CARVING-FORK GUARD.

SPECIFICATION forming part of Letters Patent No. 279,056, dated June 5, 1883.

Application filed September 27, 1882. (Model.)

To all whom it may concern:

Be it known that I, STEPHEN S. WARD, of Greenfield, in the county of Franklin and State of Massachusetts, have invented certain new and useful Improvements in Guards for Carving-Forks, of which the following is a full, clear, and exact description.

In my improved construction of guards for carving-forks the principal advantages sought over those heretofore made are greater facility and cheapness in manufacture with less hand-labor, with the result of a better working article, facility of adjustment and removal, simplicity, and durability.

15 The invention consists in a guard having a bent tongue or stirrup which is engaged by a slotted spring attached to the shank of the fork, as hereinafter described and claimed.

Reference is to be had to the accompanying drawings, forming a part of this specification, in which similar letters of reference indicate corresponding parts in all the figures.

Figure 1 is a side view of a fork fitted with my improved guard. Fig. 2 is a plan view of the fork with the guard removed. Fig. 3 is a face view of the guard-piece. Fig. 4 is a longitudinal section of the same. Figs. 5 and 6 represent modifications in the construction.

A is the guard-piece, which may be of any suitable shape or size, and is made with forked ends *a a*, to stride the neck or shank of the fork B. Between the forks *a* of the guard is formed a tongue or stirrup, *i*, the outer end of which has side lugs or projections, *i'*, above 35 which the stirrup is bent at right angles, or nearly so.

C is the retaining device, consisting of a plate of spring metal attached to the fork B by a rivet or screw, *b*, at one end, and formed at its outer end with a slot, *c*, that receives the tongue or stirrup *i* on the guard A, with its side lugs, *i'*, upon which the sides of the slot *c* take or rest, so that the guard is held in place by the spring. In order to attach the

45 guard, the end of the spring is slightly raised and the side lugs, *i'*, of the stirrups *i* are slipped under, the body of the stirrup or tongue at the same time entering the slot in the spring. In this manner the tongue on the 50 guard is engaged by the forked end of the

spring, and to hold the guard more securely the ends of the spring may be slightly depressed, so that they will prevent any tendency of the guard to slip forward and retain it firmly in position. Backward movement of 55 the guard is prevented by the bend of the tongue *i* and the end of the slot, and the guard, when raised, comes down squarely upon the spring, as is shown in Fig. 1. In this raised position the bend of the tongue *i* also causes 60 the guard to stand very firmly, with no tendency to fall forward, as is the case with fork-guards as usually made. The spring C may be made of any suitable shape, and attached by any suitable means, and in place of an open 65 slot, *c*, as shown, the spring may be simply apertured, in which case the stirrup or tongue *i* is to be inserted before the spring is attached to the fork, the lugs *i'* being at right angles to the spring. The slot in this case should be 70 longer than it is wide, to allow the entry of the tongue *i* and its retention when revolved to bring the lugs beneath the edges of the slot.

The neck or shank of the fork may be provided with an aperture or slot, as shown at *l* 75 in Fig. 5, and the stirrup or tongue *i* passed through this slot, the spring *c* being in that case attached to the under side of the fork for engaging the tongue, as shown. In this latter construction of the fork-guard the tongue 80 *m* may be left upon the end of the stirrup *i* below the lugs *i'*, as shown in Fig. 6; and in order to permit the passage of the lugs *i'* through the slot in the fork-shank, the slot being narrower than the lugs are long, the 85 arms *a a* of the guard may be caused to stand sufficiently outward from the tongue or stirrup *i* to enable the guard to stride the fork-shank obliquely to such an extent that the lugs may be caused to pass through said slot and 90 occupy a plane below the fork-shank, after which the guard is turned to bring the lugs of the tongue at right angles to the fork-shank and spring.

Having thus fully described my invention, I 95 claim as new and desire to secure by Letters Patent—

1. In carving-forks, the combination, with the bifurcated guard A, provided with the tongue or stirrup *i*, having the lugs *i'*, of the 100

spring C, secured to the fork at one end, and provided at its outer end with a slot which receives the tongue or stirrup *i* of the guard A, substantially as shown and described, and 5 for the purpose set forth.

2. The combination of the spring C, attached to the fork B and having its outer end slotted and slightly depressed, with the bifur-

cated guard A, having the tongue or stirrup *i*, formed with side lugs and having a bend 10 above the lugs, substantially as shown and described.

STEPHEN SELBY WARD.
